United States Patent Office.

LUCIUS A. DODGE, OF KEESEVILLE, NEW YORK.

Letters Patent No. 79,326, dated June 30, 1868.

IMPROVEMENT IN LUBRICATOR FOR NAIL-MACHINES.

The Schedule referred to in these Letters Patent and making part of the same.

TO ALL WHOM IT MAY CONCERN:

Be it known that I, LUCIUS A. DODGE, of Keeseville, in the county of Essex, and State of New York, have invented a new and useful Improvement in Lubricating-Devices; and I do hereby declare that the following is a full, clear, and exact description thereof, which will enable others skilled in the art to make and use the same, reference being had to the accompanying drawing, forming part of this specification, in which—

The drawing represents a partial section of the stock to which the said roller is affixed.

Similar letters of reference indicate corresponding parts.

My invention relates to improvements in means for lubricating the forging-rollers of nail-machines, such as are used in the machines patented to Daniel Dodge, August 30, 1859, and June 3, 1856, wherein a forging-roller is arranged to move rapidly around an axial support, and, when in contact with the iron to be wrought, is also caused to rotate rapidly on its own axis, the centrifugal action thereby induced greatly tending to throw off any oil or lubricant which may from time to time be applied to it.

My invention consists in providing a chamber within the stock, to which the forging-roller is secured, and on which it is carried around the above axle, provided with openings for supplying it with oil, and provided also with passages communicating with the axis of the said forging-roller, and with packing of absorbent material, and set-screws for compressing the said packing so as to regulate the flow of the oil, as will be more fully described on reference to the accompanying drawings.

A represents the stock, and B the roller, of which b b is the axle.

The stock A is arranged, in the before-mentioned nail-forging machine, in a rotary disk, around the axis of which it revolves with great rapidity, causing the pulley B to strike the metal to be forged at each revolution of the stock around the said axis.

C represents a chamber, provided in the said stock by boring, or other suitable means, and plugging up the ends of the same, as shown in dotted lines.

C' and C' represent branches of the said chamber, extending from the main portion toward the vicinity of the axle of the roller B, and which may be provided with wicking of absorbent material.

d d represent small passages, which complete the channel from the chamber C to the axle, or to the wheel near the axle.

As the centrifugal action of the said stock would cause an undue flow of oil through the said wicking to the axle, I have provided the set-screws a a, to be forced against the said wicking, so as to compress it and limit the passage of the oil.

The said stock may be provided with a passage, as shown at e, for pouring the oil into the chamber, and which may be plugged up after the chamber is filled.

Having thus described my invention, I claim as new, and desire to secure by Letters Patent—

The stock A, provided with the chamber C, the wick-chambers C' and C', passages d d, and the set-screws a a, substantially as and for the purpose described.

The above specification of my invention signed by me, this   day of   , 1868.

LUCIUS A. DODGE.
